Primary Examiner—Catherine Tuttle(74) *Attorney, Agent, or Firm*—Thorpe North & Western LLP(57) **CLAIM**

What is claimed is the ornamental design for an adjustable height basketball hoop, as shown and described herein.

DESCRIPTION

FIG. 1 is a left side view of the invention;

FIG. 2 is a right side view thereof;

FIG. 3 is a front view thereof;

FIG. 4 is a rear view thereof;

FIG. 5 is a top view thereof;

FIG. 6 is a bottom view thereof; and,

FIG. 7 is a perspective view thereof.

The phantom or broken line showing is for illustrative purposes only and forms no part of the claimed design.
